UNITED STATES PATENT OFFICE.

DENNIS MALLORY, OF EDGAR, NEBRASKA.

WRENCH.

939,728.

Specification of Letters Patent.

Patented Nov. 9, 1909.

Application filed February 9, 1909. Serial No. 476,887.

To all whom it may concern:

Be it known that I, DENNIS MALLORY, a citizen of the United States, residing at Edgar, in the county of Clay and State of Nebraska, have invented certain new and useful Improvements in Wrenches; and I do hereby declare the following to be a full, clear, and exact description of the invention, such as will enable others skilled in the art 10 to which it appertains to make and use the same.

My invention relates to new and useful improvements in wrenches and more particularly to a hand-operated combined nut 15 and pipe wrench and my object is to provide means for quickly adjusting the sliding jaw to clamp the object to be turned between the sliding and stationary jaw and a further object is to provide means for holding the 20 sliding jaw in its adjusted position.

Other objects and advantages will be hereinafter referred to and more particularly pointed out in the claims.

In the accompanying drawings forming 25 part of this application, Figure 1 is a side elevation of the wrench complete. Fig. 2 is a sectional view as seen on line 2—2, Fig. 1, and, Fig. 3 is an edge elevation of the bar employed for operating the movable 30 jaw.

Referring to the drawings in which similar reference numerals designate corresponding parts throughout the several views, 1 indicates the shank of my improved wrench, 35 to one end of which is fixed a jaw 2, and 3 indicates a movable jaw, said jaw having an opening 4 therethrough, through which extends the shank 1.

Pivots secured to the free end of the 40 shank 1, is a handle 5, said handle being adapted to be employed for adjusting the movable jaw 3 and to serve as a lever for the wrench, the pivoted end of said handle having a lateral extension 6, in which is 45 formed a slot 7, in which is pivotally secured a tongue 8 of a bar 9, the opposite end of said bar being likewise provided with a tongue 10, which enters a cavity 11 in the jaw 3, a pin 12 being entered through the 50 jaw and the tongue 10 to pivotally secure the bar to the jaw, a pin 13 being also introduced through the lateral extension 6 and the tongue 8 to pivotally secure the bar to said extension.

The shank 1 is pivotally secured at one edge of the handle 5 and to that edge

farthest from the extension 6, said shank being introduced into a recess 14 and held therein by means of a pin 15 and it will be readily seen that as the handle is swung 60 back and forth on the shank 1, the jaw 3 will be moved toward and from the fixed jaw 2.

The jaw 3 is held in its adjusted position by attaching a link 16 to the bar 9, the free 65 end of the link being adapted to engage notches 17 on one edge of the shank 1 and by providing a plurality of the notches, the jaw 3 may be held in various adjusted positions.

The meeting faces of the jaws 2 and 3 are preferably concave between their ends and their intersection with the shank 1, whereby the wrench may be employed for turning or holding a round object, said concave portions being provided with teeth 18, which are adapted to engage the surface of the round object and hold the same in a fixed position.

In applying the wrench to use, the link is 80 disengaged from the notches 17 and the handle 5 moved to separate the jaws to receive the object to be turned and after it is placed between the jaws and the handle 5 swung in the opposite direction until the object is securely clamped between the jaws, the link 16 is again swung into engagement with one of the notches, when power may be applied to the handle to swing the lever in either direction, the engagement of the 85 link with the notch, rendering the handle 5 rigid with the shank.

It will thus be seen that I have provided a very cheap and economical form of wrench and one that may be quickly applied to use 90 and by providing the meeting faces of the jaws with concavities and placing therein the teeth as shown, said wrench may be applied for turning round, as well as flat faced objects.

What I claim is:

1. A wrench comprising a shank having a fixed jaw thereon, a handle pivotally connected adjacent one of its edges to the shank, a lateral extension on said handle, a movable jaw slidably mounted on said shank, a bar pivoted at its ends to said extension and movable jaw, a link carried by the bar, said shank having a plurality of notches therein to receive said link and hold the movable 110 jaw in its adjusted position.

2. A wrench comprising a shank having a

jaw fixed at one end thereof and having notches in one of its edges, a handle pivoted to the opposite end of the shank, the pivotal point being adjacent one edge of the handle, a lateral extension on the pivoted end of the handle, a movable jaw on the shank, a bar pivotally connecting the movable jaw to the lateral extension, a link pivoted to the bar, the free end of which link is adapted to engage the notches in the shank and hold the movable jaw in its adjusted position, the

meeting faces of said jaws having concavities, the surfaces of which are provided with teeth.

In testimony whereof I have signed my name to this specification in the presence of two subscribing witnesses.

DENNIS MALLORY.
